UNITED STATES PATENT OFFICE.

JOHN H. HOLZHAUSEN, OF MILWAUKEE, WISCONSIN.

SPRING-MOTOR.

1,188,449.

Specification of Letters Patent. Patented June 27, 1916.

Application filed August 19, 1915. Serial No. 46,264.

To all whom it may concern:

Be it known that I, JOHN H. HOLZHAUSEN, a citizen of the United States, and resident of Milwaukee, in the county of Milwaukee and State of Wisconsin, have invented certain new and useful Improvements in Spring-Motors; and I do hereby declare that the following is a full, clear, and exact description thereof.

10 This invention relates to the subject of spring motors, and has specially in view an improvement in spring motors by means of which an automatic re-winding of the motor is obtained that will subserve the 15 function of delaying the time of running down after the motor has been given a full wind.

In producing a spring motor capable of performing the functions generally stated 20 above it will be understood, of course that the essential features of the same are susceptible to changes in details and structural arrangements, one simple and practical embodiment of the same being shown in the 25 accompanying drawings wherein—

Figure 1 of the accompanying drawings is a vertical longitudinal sectional view of the improved spring motor, the section being taken on the line 1—1, Fig. 2. Fig. 2 is 30 an end view. Fig. 3 is a detail fragmentary sectional view taken on the line 3—3, Fig. 2. Fig. 4 is a transverse sectional view taken on the line 4—4, Fig. 1.

The improved spring motor comprises in 35 its general organization a base or foundation 1 provided with end standards 2 and a centrally located standard 3, the standards being relatively positioned for the reception of two independent motors, to be described 40 in detail. The lower portions of the standards 2 and 3 have the two longitudinally aligned arbors 8 journaled therein and at an intermediate point, the said standards have the drive shaft 4 journaled therein. The 45 upper portions of the standards 2 and 3 have the transmission shaft 5 journaled therein, the arbors 3, drive shaft 4 and transmission shaft 5 being in parallel relation. Bracket arms 6 project laterally from 50 the standards and have the power shaft 7 journaled therein. As a detail of the invention, it is preferred that the bearings for the shafts and arbors be of the anti-friction type.

55 Each arbor 8, adjacent its ends has gears 9 loose thereon and beyond said gears, the

arbors have ratchet wheels 10 fast thereon. As will be observed by reference to Figs. 1 and 2 of the drawings, the arbors 8 project beyond the standards 2, and such projecting portions of said arbors have ratchet wheels 11 fast thereon. Holding pawls 13 are pivotally connected to the standards 2 and 3 and engage the ratchet wheels 10 to prevent reverse movements of said ratchet wheels. 65

As is clearly shown in Fig. 1 of the accompanying drawings, each arbor 8 is equipped with a pair of the gears 9, the pairs of gears forming heads for a cage structure that includes said heads and a plurality of regularly spaced head-connecting bars 14 that are suitably attached to said head, for example, by means of the lugs 15 carried by said heads and to which the bars 14 are fastened. Each arbor 8 has 75 the inner end portions of the plurality of springs 16 coiled thereon, the said inner ends being firmly fastened to the arbors, as suggested in Fig. 4 of the drawings. The outer ends of said springs 16 extend to and 80 are fastened to the bars 14.

Drive shaft 4 is provided with gears 17 that are in mesh with gears 9 of arbors 8, and transmission shaft 5 has a gear 19 thereon that meshes with a gear 18 on shaft 4. 85 The power shaft 7 has a sprocket or other connection 20 with transmission shaft 5. Transmission shaft 5 has its ends provided with bell-crank levers 21, the free ends of said levers having adjustable rod connections 22 with crank plates 23 carried by the ends of power shaft 7. The bell-crank levers 21 have rod connections 24 with cranks 25 mounted on the outer ends of the arbors 8, and said cranks 25 have spring-pressed pawls 26 pivoted thereto and in engagement with the ratchets 11. 95

From the foregoing description it will be understood that the springs 16 are primarily wound by rotating the arbors 8 and 100 that when the controlling mechanism (to be described) is released, the expansion of the said springs causes the cages to rotate, and through the described gear connections 9 and 17, and 18 and 19, shaft 5 is rotated 105 and through the sprocket connection 20, the rotary movements of shaft 5 are communicated to power shaft 7, it being understood, of course that shaft 7 may be connected to any suitable or desirable machine 110 for which the power from said shaft is utilized as the driving medium. The rotary

movements of shaft 7 cause levers or cranks 25, through the rods 22 and 24, bell-crank levers 21 and crank plates 23, and pawls 26 to intermittently rotate ratchets 11, and said 5 ratchets 11 being fast on the arbors 8, the arbors will rotate with said ratchets. The springs 16 being fast on arbors 8, it is obvious that the described rotation of said arbors will tighten the springs about the 10 arbors in such a manner that running down of all the springs, after a preliminary winding is delayed. In operation the two series of springs are thus alternately wound on their arbors 8, and all expand at the same 15 time to rotate the cages. Such rotation of the cages, in addition to furnishing the power for driving the shaft 7, also causes a partial rewind of the springs about the arbors 8 in an intermittent manner, as de- 20 scribed.

A controller and governor for the motor is provided and which may be of the form shown in detail in Fig. 3 of the accompanying drawings, and referring to said figure it will be seen that said controller and governor includes a gear 27 fast on shaft 7 meshing with a gear 28 fast on a controller shaft 29, said shaft 29 having one end journaled in an arm 30 depending from bracket 30 6 and its other end journaled in standard 3. A balance wheel 31 is fast on shaft 29 and also a governor including a stationary collar 32, a slidable collar 33, springs 33^a connecting the collars, and weights 34 carried 35 by the springs. The collar 33 has a grooved portion 35 that is engaged by a ring 36, the ring being carried by rods 37 extending to a plate 38 fast on an adjusting screw 39 mounted in an offset arm 40 depending from bracket 6. The screw 39 is provided with a suitable handgrip 41 by means of which 40 said screw may be manually manipulated to

cause ring 36 to adjust the governor and also to cause said ring to act as a brake on collar 33 and thereby control the operation 45 of the motor.

I claim as my invention:—

1. In a spring motor the combination of a frame, shafts and a pair of arbors having bearings in the frame, a cage loose on each arbor, a series of springs connecting each arbor and the cage therewith, gearing by which motion is transmitted from both cages to the shafts, a pair of ratchet wheels fast on each arbor, pawls carried by the frame and engaging the ratchet wheels, a lever on each arbor, means operated by the levers for causing the arbors to rewind the springs, and means for intermittently operating the levers. 60

2. A spring motor comprising a frame provided with standards arranged in spaced relation, a pair of arbors journaled in the standards, a cage loose on each arbor and including end gears and connecting bars, a series of springs fastened to the bars and the arbors, ratchets fast on the arbors, pawls carried by the frame standards and engaging the ratchets to prevent reverse movement of the arbors, a power shaft having 70 gear connections with the cages, means operated by the power shaft for intermittently rotating the arbors to rewind the springs and a combined governor and manually operable controller for the motor. 75

In testimony that I claim the foregoing I have hereunto set my hand at Milwaukee, in the county of Milwaukee, and State of Wisconsin, in the presence of two witnesses.

JOHN H. HOLZHAUSEN.
